COMBINED SCREEN AND TABLE

Neal W. Liebel, Erie, Pa.

Application October 22, 1947, Serial No. 782,587

1 Claim. (Cl. 311—2)

1

This invention relates generally to useful and ornamental screens or covers for concealing domestic articles or devices of unsightly appearance and it relates more particularly to a useful and ornamental combined table and screen for concealing a sewing machine.

At the present time there are thousands of old type sewing machines in use, particularly of the drop-head type. These sewing machines are unsightly in appearance and in the small homes of today, no suitable storage space is provided for them. Furthermore, these machines are heavy and cannot be moved by the average housewife.

It is, accordingly, an object of my invention to provide a useful and ornamental unit which may be used for concealing a sewing machine or the like, which is simple in construction, economical in cost, economical in manufacture and easy to install.

Another object of my invention is to provide a novel concealing cover or screen for a sewing machine or the like which provides a table surface for any desired use.

Another object of my invention is to provide a novel concealing screen or the like which may be assembled and knocked down in a minimum of time with a minimum of effort.

Another object of my invention is to provide a novel concealing screen for a sewing machine or the like which is extremely light in weight so that it can be placed over a sewing machine by a comparatively small woman.

Another object of my invention is to provide a concealing unit for a sewing machine which has ornamental features as well as a flat table top which may be utilized as a serving table, vanity table, or for any other purpose desired.

Another object of my invention is to provide a novel combined screen and table for concealing a sewing machine which may be easily and cheaply packaged.

Other objects of my invention will become evident from the following detailed description, taken in conjunction with the accompanying drawings, in which

Fig. 1 is a perspective view of my novel combined screen and table;

Fig. 2 is a perspective view taken from the rear of my novel combined screen and table; and

Fig. 3 is a fragmentary sectional view showing engagement of the side panels and table top member to the frame of my novel device.

Referring now to the drawings, I show in Figs. 1, 2 and 3, side panels 1 and 2 each having a curved cut-out portion 3 and 4 principally for

ornamental purposes. A front panel 5 is cutaway at 6 principally for ornamental purposes. Molding 9 is disposed crosswise of the front panel 5 and an upwardly extending molding 10 gives the panel 5 the appearance of having drawers. The molding 9 and 10 also serves as stiffening members for the front panel 5. Short strips of molding 11 are provided to simulate door handles. A generally U-shaped frame 12 has a grooved portion 13 for nesting and securing the upper ends 14 of the side panels 1 and 2 and the front panel 5. The upper side of the frame 12 has an L-shaped groove 15 cut-out therefrom to receive the marginal portion of a top 16 which may be of any suitable material such as plywood. The top 16 may be secured to the frame 12 by screws, nails, or it may be glued thereto as desired. Vertically extending brace members 17 are preferably provided to strengthen the unit. The outer side 18 of the frame 12 is curved to present an ornamental appearance. Cross-piece 19 is secured to the underside of the top 16 to prevent sagging. Vertically extending brace members 20 are also disposed on the side panels 1 and 2. In the construction of my novel device, I select comparatively cheap, light wood members, such as plywood. Moldings 9 and 10 are then secured to the front panel 5 and brace members 17 are secured adjacent the side edges of the back of the front panel 5 by screws, nails, or glue. The moldings 11 are then secured to the front panel to simulate handles by any suitable means. The cut-out portions 3, 4 and 6 may have different curved lines or straight lines as desired. The side panels 1 and 2 and front panel 5 are then secured together by screws, nails, or glue, the brace members 17 providing corner members to which the side panels 1 and 2 and the front panel 5 are secured. The upper ends of the side panels 1 and 2 and front panel 5 are then nested in the groove 13 in the frame 12. The upwardly extending brace members 20 are secured to the sides 1, and 2 by screws, nails, or glue before connection of the side panels 1 and 2 to the front panel 5. The top 16 is disposed in and secured in the grooved portion 15 of the frame 12, preferably before assembly to the side panels 1 and 2 and front panel 5. It will be seen that my novel device may be packaged in a comparatively flat knocked-down condition and it may be easily assembled at the place of distribution or in the home. Three flat units—(1) top 16 with brace member 19 attached in frame 12; (2) side panels 1 and 2 with brace members 20 attached, and (3) front panel 5 with moldings 9, 10, and 11 and

brace members 17 attached—may be packaged in a flat box without marring any finish on any of the pieces. Seating members 21 or casters are preferably disposed on the bottom of the brace members 17 and 20 to permit my novel screen and table to be slid or pulled on a floor or rug.

My novel combined screen and table is very light in weight, simple in construction, easy to assemble and disassemble, economical in cost and readily adaptable for use as a serving table, 10 vanity table, or for any other purpose where a screen or cover and a table top is needed, pleasing in appearance and one which may be finished to individual taste.

Various changes may be made in the specific 15 embodiment of my invention without departing from the spirit thereof or from the scope of the appended claim.

What I claim is:

A combined screen and table top member comprising a screen of generally U-shape having a front panel and side panels, a generally U-shaped frame having a groove extending longitudinally in the bottom side thereof and nesting the upper ends of said panels and also having an L-shaped 25 groove on the upper inner side thereof, vertically extending brace members secured to said panels,

and a flat table top member having three marginal edges thereof disposed in the L-shaped groove of said frame.

NEAL W. LIEBEL.
